UNITED STATES PATENT OFFICE.

OTTO S. BEYER, OF BROOKLYN, NEW YORK, ASSIGNOR TO E. W. BLISS COMPANY, OF NEW YORK, N. Y., A CORPORATION OF DELAWARE.

POWER PUNCHING PRESS.

Application filed January 17, 1927. Serial No. 161,617.

This invention relates to presses for punching, embossing, or other work on metal or other material, and is designed to provide a press capable of operating at high speed and doing heavy work.

The invention is embodied in a press having a relatively short stroke and capable (with a suitable automatic feeding mechanism) of making, for example, 300 punching 10 strokes per minute under a punching pressure of 50 tons.

The preferred embodiment of the invention is shown in the accompanying drawings, wherein,—

15 Figure 1 is a rear elevation of the press, partly in vertical section, the portion above the dotted line *a*—*a* being a mid-section on the line 1—1 in Figs. 2 and 4, and the portion below that line being in the plane of 20 the line 1^a—1^a in those figures.

Fig. 2 is a side elevation of the lower part of the press, the upper part being a vertical transverse mid-section in the plane of the lines 2—2 in Figs. 1, 3 and 4.

25 Fig. 3 is a horizontal section, partly in plan, the sectional portion being in the planes of the lines 3—3 in Figs. 1 and 2.

Fig. 4 is a horizontal section taken mainly in the plane of the line 4—4 in Fig. 2, 30 but the plunger being in the plane of the line 4—4 in Fig. 5.

Figs. 5 and 6 are side and front elevations of the plunger.

35 Figs. 7 and 8 are a side elevation and plan of the saddle.

Figs. 9 and 10 are a plan and side elevation of the saddle rest or pad.

The specific machine shown in the drawings has a main frame comprising a base A supported upon a sub-base or pedestal B, and supporting a bed C, an open upright frame D, and a press head E. The parts A, D, E are tied together by four tie rods F which pass through them and have nuts on their ends. This construction of frame 40 is convenient, but not essential.

The press head E supports a power shaft G, the middle portion of which is reduced, as shown in Fig. 1, to form an eccentric *g*.

50 The shaft turns in bearing sleeves H H which are housed in a transverse bore in the press head E. The shaft is driven in any suitable manner, preferably through a clutch of the well-known type, from a fly-wheel I which is clutched to the shaft under

control of a clutch-operating arm *i* operated by a treadle *j* in the usual and well-understood manner. The fly-wheel I may be driven in any suitable manner, being shown as formed as a gear meshing with a pinion *h* 60 on the shaft of an electric motor J.

Motion is communicated from the eccentric *g* to a punch head K to reciprocate the latter rapidly in vertical direction, so that a punch *m* carried by this head and coacting with a die *n* supported on the bed C 65 may punch or otherwise act upon a strip or other sheet of metal or other material which is fed between the punch and die in usual manner. At *n'* is shown the usual stripping 70 plate.

The means for communicating motion from the eccentric *g* to the punch head K will now be described. Just over the head K is a plunger L, shown separately in Figs. 5 and 6. 75 This plunger has a widely extended foot or base flange *k* which is bolted to the head K by screws *b* *b* (Fig. 4); and it has a tubular sliding portion *l* which slides within a vertical bore *p* in the press head E. It is preferable to make the sliding portion *l* and the bore *p* cylindrical. The sliding portion *l* is cut through at *q* to form opposite openings which afford a clear space for the passage of the shaft G, and also preferably permit partial entry of its bearing bushings H. These 80 bushings are utilized to guide the slide *l* and prevent its executing any rotary movement on its vertical axis; and for this purpose the ends of these bushings are made square, so 85 that they terminate in parallel vertical planes where they abut against the surface portions *r* forming the margins of the openings *q*, this abutment being clearly shown in Fig. 3, and thereby a vertical slideway or 90 guide is formed which restrains the plunger to an upright sliding movement without possibility of turning. Engaging the under side of the eccentric *g* is a saddle M, shown separately in Figs. 7 and 8. This saddle rests 95 upon a support or pad P shown separately in Figs. 9 and 10, and which constitutes essentially a part of the plunger L, but is for convenience made separate therefrom. Between the pad P and the base portion *k* of the 100 plunger is some suitable connection whereby the pad may be adjusted vertically with respect to the plunger; this adjustment is best afforded by means of a wedge *s* introduced between the pad and plunger, as shown in 105

110

Fig. 2, and having an adjusting screw *t* for setting the wedge out or in. In Fig. 4 the saddle *M* and pad *P* are removed, so that the wedge *s* is seen in place. The wedge passes 5 through an opening *u* in the lower part of the plunger, best shown in Fig. 6.

The upstroke of the punch head is effected by retracting springs *Q* *Q* which may be arranged in any convenient manner. Preferably they are mounted on the press head *E*, and for compactness are dropped into recesses in that head, as shown in Figs. 2 and 3. Each of the springs *Q* is shown as comprising two compression springs of equal 15 stress, one nested within the other according to a well-known construction, and exerting an upward stress on rods *R* *R* which extend down through the springs and through openings in the head, and are fastened at their 20 lower ends to the base flange *k* of the plunger *L*, as shown in Fig. 2. The springs are preferably enclosed in tubular casings *v*.

The punch head *K* requires to be accurately guided in its vertical movement, and this in 25 the construction illustrated is accomplished by giving it a sliding engagement with four fixed studs *T* *T* fastened in the bed *C* and projecting upwardly therefrom, as shown in Fig. 2, and having sliding engagement with 30 bushings *w* fixed in the head *K*, as shown in Fig. 1. The studs *T* *T* are spaced widely apart so as to be nearly aligned with the posts *D* *D* and rods *F* *F*, whereby to leave a wide 35 space between them for giving access to the punch and die.

In operation the rotation of the eccentric imparts an oscillating motion to the saddle *M*, which is free to slide on the pad *P*. As 40 the eccentric center descends, the downward movement is transmitted through the saddle and pad to the plunger and punch head. The lateral movement of the eccentric is imparted to the saddle, which slides laterally on top of the pad *P*. The return or upstroke is effected by the stress of the spring *Q* *Q*. The 45 construction is such that with a short stroke an extremely rapid reciprocation may be imparted to the punch head, so that the press may be driven at high speed. The machine 50 is very compact and amply strong for heavy work. The punch head affords a direct application of the working pressure. The capacity for high speed is due to the minimizing of size and weight of the reciprocating parts. This reduces the mass of the parts 55 to be driven through the clutch, and relieves the clutch of the severe shock of starting a heavy press, which of itself enables a higher starting speed to be imparted. The punch head is adequately guided by the fixed studs *T*, which give accurate alignment, and avoid 60 the weight of the long sliding head, moving in prolonged vertical slideways, heretofore commonly used.

65 The invention may be modified in its me-

chanical details, its construction being variable in accordance with the work to be performed, and within the scope of the appended claims.

What I claim is:

1. A power press of the described type comprising a frame, an upright cylindrical tubular slide having bearings in said frame above and below the driving shaft, the driving shaft intersecting said slide having bearings in the 70 frame on opposite sides of the slide, and having an eccentric within the slide, a punch-head carried by the slide, means within the slide for communicating motion from said eccentric to the punch-head, and yielding 75 means for drawing the punch-head upwardly.

2. A power press according to claim 1, the punch-head located beneath the slide and projecting laterally beyond the slideway in the frame, and said yielding means consisting of 80 springs connected with the laterally-projecting 85 portions of the punch-head.

3. A power press comprising a fixed frame having an upright cylindrical slideway, an upright tubular slide movable in said slideway, a transverse shaft intersecting said slide, having bearings in said frame, the slide having bearings above and below the shaft, a punch-head attached beneath said slide, upright guiding means for preventing rotative 90 displacement of said slide, and means within 95 the slide for communicating motion from said shaft to the punch-head.

4. A power press comprising a fixed frame having a vertical cylindrical slideway, a plunger having a cylindrical portion working 100 in said slideway, and having guiding faces in vertical planes intersecting its cylindrical portion, a transverse shaft, and bearing bushings for said shaft within said fixed frame, the ends of said bushings engaging said guiding faces to prevent rotary displacement of 105 said plunger, and a punch-head carried beneath said plunger.

5. A press of the described type comprising a shaft having an eccentric, a vertically moving hollow plunger and punch-head, the shaft intersecting the plunger with its eccentric within the plunger, a saddle engaging 110 the under side of the eccentric, and a pad 115 within the plunger supporting said saddle and communicating the downward working thrust therefrom to the plunger and punch-head, with means between the pad and punch-head for adjusting the relation of the pad and punch-head whereby to set the latter up or down.

6. A press according to claim 5, with a wedge between said pad and punch-head, and means for adjusting such wedge whereby to 120 vary the relation between the pad and punch-head to set the latter up or down.

7. A press comprising an upright plunger provided with a tubular slide movable on its 125 vertical axis, an upright frame symmetrical 130

- with said axis, comprising a bed, four uprights thereon, and a head above said uprights, said head having an upright slideway for said slide, and having transverse bearings 5 on opposite sides of the slide, a horizontal shaft in said bearings having an eccentric within the slide, a punch-head carried by the plunger below the head, and means within the tubular slide for communicating motion 10 from the eccentric to the slide.
8. A press comprising an upright tubular slide movable on its vertical axis, an upright frame symmetrical with said axis, having an upright slideway for said slide, and having 15 transverse bearings on opposite sides of the slide, a horizontal shaft in said bearings having within the slide an eccentric wholly within the radius of the shaft so that the shaft may be removed endwise from its bearings, 20 and means within the tubular slide for communicating motion from the eccentric to the slide.
9. A press according to claim 8, the frame having bushings seated within its head forming said bearings. 25
10. A press according to claim 8, the means for communicating motion comprising a saddle engaging the lower half of the eccentric and movable within the hollow of the tubular slide, in horizontal direction relatively to 30 the slide.
11. A press according to claim 7, the punch-head working between two pairs of said uprights.
12. A power press having a fixed vertical 35 frame transversely bored for receiving shaft bushings and having vertical slideways both above and below said bore, a hollow vertical slide extending above and below such transverse bore and guided by said slideways, 40 bushings in said transverse bore on opposite sides of said slide, a shaft passing through the slide, having bearings in said bushings, and having between said bushings an eccentric of smaller diameter than the shaft, the 45 slide enclosing said eccentric, and means within the slide for communicating motion from the eccentric to the slide, whereby the shaft is removable endwise through a bushing and the slide has guiding bearings on 50 both sides of its connection with the eccentric.

In witness whereof, I have hereunto signed my name.

OTTO S. BEYER.
